UNITED STATES PATENT OFFICE.

HAROLD B. BRISTOL, OF ST. LOUIS, MISSOURI.

LOOSE-LEAF BINDER.

1,253,206.

Specification of Letters Patent. Patented Jan. 15, 1918.

Application filed November 1, 1916. Serial No. 128,924.

To all whom it may concern:

Be it known that I, HAROLD B. BRISTOL, a citizen of the United States, residing at St. Louis, State of Missouri, have invented 5 certain new and useful Improvements in Loose-Leaf Binders, of which the following is a full, clear, and exact description, reference being had to the accompanying drawings, forming a part hereof.

10 My invention has relation to improvements in loose-leaf binders; and it consists in the novel features of construction more fully set forth in the specification and pointed out in the claims.

15 The present invention is primarily directed to improvements in binders for sheet music, although obviously the same is applicable to the binding in book form of loose sheets generally. The object sought is to

20 construct a binder which will entail a minimum consumption of time in binding a given sheet or in removing a sheet from the binder; one which will accommodate a maximum number of sheets without destroying the 25 freedom of the turning of the sheets or affecting the desired disposition of the sheets for purposes of reading the matter printed thereon; one containing a minimum number of parts considering the superior character

30 of the binder; one whose component parts are easily constructed and readily assembled or taken apart; one which is light, durable, and not clumsy to handle or operate; and one possessing further and other advantages 35 better apparent from the following detailed description of the invention in connection with the accompanying drawings, in which—

Figure 1 represents a plan of the binder when assembled, one of the covers being 40 partly broken away to expose a portion of a sheet of music; Fig. 2 is a back view thereof; Fig. 3 is a longitudinal section on the line 3—3 of Fig. 1; Fig. 4 is an inside plan of the binder with one of the covers 45 swung open, parts being broken away; Fig. 5 is an enlarged cross-section through the “back” of the book formed by the assembling of the covers, on the line 5—5 of Fig. 4; Fig. 6 is a cross-section on the line 6—6

50 of Fig. 1 showing the covers in closed position; Fig. 7 is an enlarged inner face view of one of the sections of the frame to which the covers of the binder are hinged, and by 55 which the leaf-securing posts are carried; Fig. 8 is a longitudinal section on a central

plane through the hinge-frame taken on the line 8—8 of Fig. 7; Fig. 9 is a plan of the removable take-up member or follower; Fig. 10 is an end view thereof; Fig. 11 is a side view of the follower; Fig. 12 is a plan of a portion of the hinge-strip or leaf carrier to which the leaf is pasted, one of the layers or plies of the strip being broken away; Fig. 13 is a cross-section of the strip on the line 13—13 of Fig. 12; Fig. 14 is a plan of the slide by which the leaf-anchoring posts are secured to the longitudinal strips of the frame to which the covers are hinged; Fig. 15 is a side view 60 thereof; Fig. 16 is an elevation of one size of leaf-anchoring post; Fig. 17 is an end view thereof; and Fig. 18 is an elevation of a larger size of post.

Referring to the drawings, C, C, represent 65 suitable covers or lids of cardboard or other suitable material with an inside finish or layer of paper *a* mounted on a sheet of cloth *a'*, and an outside layer or sheet of leather or equivalent pliable material *b*, the 70 sheets *a'* and *b* being extended beyond the edge of the cover to form a hinge *b'* therefor as shown in Fig. 5. The free edge of said extension *b'* is folded over the lip 1 bent from the leg 2 of the longitudinal rigid 75 metal strip 3 which forms the inner layer of one of the sections of the frame to which the leaves are anchored. The marginal fold *c* thus formed on the hinge *b'* is clenched between the lip 1 and leg 2 whereby the 80 cover or lid is securely fastened to the strip 3 (Fig. 5). Inasmuch as both sides of the 85 binder are alike, a description of one cover and its associated parts will be sufficient for our purpose, and reference numerals 90 applied to parts on one side will be used to 95 designate corresponding parts on the opposite side.

Mounted on the strip 3 is a second or outer strip 4 having marginal or side inwardly 100 foldable portions *d* bent parallel to the plane of the outer face of the strip thereby forming grooves or ways *w* for suitable slides 5, said slides terminating in outwardly turned lips or finger-holds *h*, *h*, by which the slides 105 may be manipulated. The slides are limited in their longitudinal movement by the lips or burs 6 punched from the outer strip 4 and bent at substantially right angles thereto (Fig. 8) the lips being spaced sufficiently 110 apart to permit the slide to perform its necessary function to be hereinafter fully

described. The punching of the members 6 from the strip 4 necessarily leaves openings or slots s in the strip. These slots are availed of for the accommodation of the 5 clenching lips 7 punched from the inner strip 3, said lips being passed through the slots s and bent over against the strip 4. The two strips are thus firmly united to one another, the whole forming a rigid composite strip or longitudinal member for the support of the cover or lid C. The punching of the lips 7 from the strip or plate 3 necessarily leaves slots s' opposite the slots s in the strip 4. The slide 5 is provided at 10 one end with a large substantially circular opening O communicating with an elongated outwardly tapering slot O' the faces t of the tapering sides being beveled for a purpose presently to appear.

20 The longitudinal rigid members or composite strips formed by the strips 3, 4, united in the manner above described serve not only as the means for supporting the covers C, but as elements of a frame to which the 25 leaves of the binder are anchored, the devices to which the leaves (or rather the leaf-carriers) are directly attached being fastened to and between said longitudinal members by the locking slides 5, there being as 30 many pairs of slides as there are leaf anchoring devices. These devices are in the form of posts 8 which are preferably cylindrical as shown. The posts terminate in reduced portions 8' which are provided with annular grooves m thereby leaving the reduced necks n as shown to best advantage in Fig. 7. The members composed of the strips 3, 4, are provided with openings for receiving the terminals 8' of the posts, the portion of 35 the terminal 8' between the groove m and the body of the post being a shade less than the thickness of the strips or plates 3, 4, thereby bringing the grooves contiguous to the outer face of the strip 4, that is to say, 40 in position to permit the slide 5 to rest against said face. The openings in the strips 3, 4, are only sufficient to allow for the insertion of the reduced terminals 8' of the posts, so that when the terminals are 45 fully inserted, the strips bear against the offsets or shoulders formed between the terminals 8' and the peripheries of the posts, the posts being thus shouldered to the strips as fully shown in Fig. 8. The opening O 50 in the slide 5 is of larger diameter than the diameter of the post terminal 8', so that when the slide is moved to bring the said opening opposite the said terminal, the post may be withdrawn from the strips 3, 4, 55 thereby permitting a disassembling of the parts. By moving the slide in the opposite direction, the converging sides of the elongated opening or slot O' are brought into the groove m , and by the time the slide 60 is shoved the full distance in said direc-

tion, the rounded base and sides of the slot hug the neck n between the side walls of the groove, thereby locking the post to the composite strip or member formed of the strips 3, 4, as shown in Figs. 7 and 8. The sloping faces t of the sides of the slot O' facilitate the movement of said sides into and out of the groove m .

The composite rigid longitudinal members formed by the assembling of the strips 75 3, 4, together with the posts 8 connecting the same constitute a frame in which the said longitudinal members serve as the means for the direct support of the covers or lids C, C, and the posts 8 as the means 80 for the anchoring of the leaves. This frame is readily disassembled or taken apart by the simple movement of the slides 5 to positions where the openings O come opposite the terminals 8' of the posts. This allows for the withdrawal of the posts from the longitudinal member; and if the slides on both sides are thus manipulated the posts may be detached altogether. Usually, however, the posts are left fastened to the 85 strips of one of the covers when occasion arises to insert a fresh leaf or leaves L into the binder. By making the posts detachable from both of the longitudinal members of the frame, different lengths of posts may 90 be utilized. Thus in Fig. 16 is shown one length of post, and in Fig. 18 a post of greater length, the size of post used depending on the number of leaves to be bound between the covers of the binder. As well 95 understood by those skilled in the art, the leaves L are not as a rule secured directly to the posts 8, it being the practice to equip the posts with a series of leaf-carriers or hinge-strips to which the leaves are pasted as 100 occasions arise to bind fresh leaves between the covers. The leaf-carrier is in the form of a strip 9 of cloth or other suitable material to one side of one of the faces of which is cemented or glued a paper strip 10 having a 105 detachable section 10' which prevents successive strips 9 adhering to one another, said section being severable along a series of perforations e , the strip 9 being provided adjacent its free edge on the side facing the section 10' with a layer of gum or adhesive r to which a leaf L is pasted after the section 10' of the paper strip has been torn off. To properly position the leaf L over the layer of gum r a line x is marked on the strip 9, these lines insuring a uniformity in the mounting of the several leaves to be bound. To prevent the strip 10' from accidentally adhering to the layer of gum r on the strip 9 before a leaf is attached thereto, the inner face of the section 10' is coated with paraffin or some equivalent non-adhesive material. This leaves the section 10' 110 always free from the strip 9, the said section being torn off when occasion requires 115

120 the strip 9 before a leaf is attached thereto. 125 the inner face of the section 10' is coated with paraffin or some equivalent non-adhesive material. This leaves the section 10' always free from the strip 9, the said section being torn off when occasion requires 130

and a leaf pasted over the gummed side of the strip 9. The strip 9 is of course flexible and readily folds along the line y immediately adjacent the layer of cement i by which the strips 9 and 10 are held together (Fig. 12). The several leaf-carriers are provided with openings A through which the posts 8 are passed before the longitudinal strip members (3, 4,) are locked to the posts by the slides 5. When only a few sheets are between the covers, it is desirable in order to keep these sheets together, to interpose a take-up or follower between the last sheet of the series and the adjacent lid or cover C. This follower is on the order of that shown in detached view, Figs. 9, 10, and 11, that is to say, it consists of a metal strip 11 provided with side folded edges or stiffening beads p , suitable resilient outwardly flexed arms 12 being stamped from the body of the plate, said arms engaging one of the strips 3, opposite the last leaf of the series (Figs. 5 and 6), the follower being provided with openings R adapted to be passed over the posts 8.

Preferably, the leaf-carriers are passed over the posts only as fast as needed, it being the better practice to make use of the take-up or follower 11 when only a few leaves are between the covers. Unless occasion arises to remove the posts altogether for the purpose of substituting posts of different length, it is only necessary to detach one of the longitudinal strip members of the frame above referred to, leaving the ends of the posts on one side free to be received by the openings A of any desired number of leaf-carriers; and when the proper number of carriers have been passed over the posts, the strip member of the frame is locked to the posts by the slides 5 (as already described), the leaves L being previously pasted to the strips 9 of the several leaf-carriers, the sections 10' thereof being first torn off along the perforations or dents e as fully pointed out above.

It may be stated in passing that while the travel of the slides 5 would necessarily be limited by the length of the opening represented by the openings O, O', it is desirable when the slide is moved to the releasing or unlocking position (dotted position in Fig. 7) that the center of the circular opening O be coincident with the axis of the post 8; and when moved to the locking position that the rounded terminal of the closed end of the slot O' engage the periphery of the neck n of the terminal 8' of the post. The length of the stroke of the slide 5 in either direction when performing its function properly is a trifle less than the stroke permitted by the full length of the combined openings O, O'; and to insure arrest of the slide at the proper points is the purpose of the lips 6 or burs 6, 6. The position of these lips is

such that when the slide is moved say to releasing position, it is arrested at the proper point to allow an annular clearance between the walls of the opening O and the periphery of the post terminal 8', so that the posts 70 may be instantly withdrawn from said openings and the strip member removed for the purpose of adding new leaves to the binder. When the several component parts of the binder are assembled, the same forms a book 75 from which however the conventional "back" is absent, that is to say the book lacks the usual connecting strip or web between the lids or covers. The only connection between the covers is the series of posts 8, a gap D 80 being left between the hinge-axes of the covers, the width of this gap depending on the length of the posts. Thus the covers instead of being permanently connected together by a back are separable from one another, it 85 being possible to detach either cover at will, and whenever occasion arises to slip fresh leaf carriers over the posts. Obviously, the details of the binder may be changed in many respects without involving a departure from the spirit of my invention. By making the portion of the post terminal 8' between the groove m and post slightly less than the thickness of the strip 3, 4, so as to clear the slide 5, the latter operates to 90 effectively wedge the post to the strip, the jamming or wedging of the slide (when moved to locking position) between the strip and the outer side wall of the groove m firmly locking the post to the strip. 95

Having described my invention what I claim is:

1. In a loose-leaf binder, a pair of elongated outer strips, a pair of elongated inner strips projecting laterally beyond the outer strips and provided with inwardly-bent legs, and covers hinged to the leg portions of said inner strips.

2. In a loose-leaf binder, a lid carrying member comprising an elongated strip provided on one side with a leg to which the lid is hinged, a second strip superposed thereover and provided with slits or openings, and lips punched from the first strip and passed through the slits of the second strip, 115 and folded against the outer face of said second strip, thereby forming a rigid composite strip or member.

3. In a loose-leaf binder, a lid-carrying member comprising an elongated strip provided on one side with a leg bent at an angle to the strip, said leg having a lid hinged thereto, a second strip superposed thereover and provided with burs or lips punched therefrom and bent outwardly, lips punched from the first strip at points opposite the openings formed in the second strip as a result of the punching of the burs therefrom, and passed through said openings and bent against the outer face of the second strip, 120 125 130

a slide mounted on the second strip and operating between the burs punched from the second strip, the composite strip thus formed being provided with openings for the reception of suitable posts engaged by said slide.

4. In a loose-leaf binder an elongated strip having a leg on one side bent at an angle thereto, said leg being provided with a lip bent against the leg, and a lid provided with a flexible hinge-strip having its edge folded to enter between the leg and lip aforesaid, the lip being clenched against the strip to securely fasten the same to the leg.

5. In a loose-leaf binder, a pair of elongated outer strips, a pair of corresponding inner strips provided with inwardly bent side portions or legs, covers hinged to said bent portions, spacing devices separating the inner strips, and means on the outer strips for locking the spacing devices to the several strips.

6. In combination with an elongated mem-

ber, a slide mounted thereon and provided with a slot elongated lengthwise with the member and having its sides approaching one another, said sides being beveled or wedge-shaped, a post inserted through the longitudinal member and passed loosely through the slot of the slide, said post having a terminal provided with an annular groove traversed by the sides of the slot, the portion of the slide beyond and adjacent to the narrow terminal of the slot operating to wedge between the outer side wall of the groove and the adjacent face of the longitudinal member when the slide is moved to one of its extreme positions, thereby locking the post to the longitudinal member.

In testimony whereof I affix my signature, ⁴⁰ in presence of two witnesses.

HAROLD B. BRISTOL.
